STEAM SPRAY SWEeper

Edward A. Rudigier, Baltimore, Md., assignor to
Standard Oil Development Company, a cor-
poration of Delaware

Application April 4, 1939, Serial No. 265,987

4 Claims. (Cl. 196—126)

The present invention relates to a method and means for preventing the deposition of solid or semi-solid materials on the bottom of a container for liquids. More particularly, the invention relates to a method and apparatus for inhibiting incrustation of the bottom of a shell still in the distillation of petroleum oils or other liquids tending to deposit coke or the like when heated.

In the conventional distillation of petroleum oils in a shell still, with or without the introduction of steam to assist in the removal of lighter fractions, it has been found that, that portion of the shell which is exposed to the hot combustion gases and to the radiant heat of the furnace, tends to burn out quite rapidly. Primarily, this has been due to the rapid incrustation of the still bottom with coke produced by heating of the oil. Although for the most part the coke is produced as fine particles, it settles to the bottom and there, under the influence of the higher temperature directly above the furnace combustion chamber, becomes compacted and solidified into a flinty mass, extremely difficult to remove. By reason of the poor heat conduction characteristics of this carbonaceous deposit, it causes over-heating of the metal to which it adheres. Continued and unequal over-heating of the shell causes the plates to buckle and to burn out. To correct the existing conditions, it is the object of this invention to maintain a constant and positive agitation of the liquid in the still adjacent the inner surface of the still bottom and prevent settlement of the solid material present or formed by heating the liquid.

The invention is fully set forth in the following specification and may be clearly understood therefrom when read in conjunction with the accompanying drawings, in which

Fig. 1 is a vertical section along the longitudinal axis of a still installation;

Fig. 2 is a vertical cross section of the same still, along the line II—II, and

Fig. 3 is an enlarged cross section of a portion of the apparatus.

Referring now to the drawings and Fig. 1, the numeral 1 designates a still shell. The numeral 2 designates I-beams bracing the shell and carrying bearing members 3. A steam pipe 4 is supported in said bearings for oscillating movement therein. The pipe 4 is provided with swing joints 5 through which a steam connection is made with supply pipes 6 passing out of the shell as at 7 and 8, respectively.

A discharge pipe 9 is disposed in closely spaced

relation to the shell floor, supported by means of pipes 10 and cross-members 11, the former providing steam connections between the distributing pipe 4 and discharge pipe 9. Counter weight members 12 are secured to the pipe 4 to partially compensate for the weight of pipe 9 and the connecting frame-work. Because of the obstruction of other equipment within the shell, such as the float gauge mechanism 13, it is sometimes necessary to use a shortened distributing pipe. In such instance, as shown, the discharge pipe need not also be of reduced length, the portion 14 which extends beyond the distributing pipe 4 being suitably braced, as by angle stiffener 15. The discharge pipe 9 is provided with jet members 16 along its lower surface, which extend downward into closer relation with the bottom of shell 1 discharging fine jets of steam against the bottom at high velocity. The disposition and structure of one of these jets is more clearly shown in the enlarged view in Fig. 3.

The structure comprising the distributing pipe 4, the connecting pipes 10, the cross-members 11 and discharge pipe 9 constitutes the sweeper mechanism. This sweeper is oscillated in the bearings 3 by means of a lever arm 17 mounted on the distributing pipe 4, connecting rod 18 and push rod 19 extending through the shell by means of the packing nut assembly 20, secured to the shell. The rod 19 is connected to a source of power not shown. Reciprocating motion imparted to the push rod 19 is converted into oscillatory motion of the sweeper through the connecting rod 18 and the arm 17. The arc through which the sweeper moves is, of course, dependent upon the length of the push rod thrust, and may be readily adjusted as required. The extreme positions of the sweeper shown by dotted lines at A and B in Fig. 2 are preferred for most installations, but the extent of such movement may be increased or decreased at will.

As mentioned above, the discharge pipe 9 may be fitted with nozzle or jet members 16 for the high velocity discharge of steam against the bottom wall. A typical jet member is illustrated in Fig. 3. It comprises a small section of pipe threaded into an opening in the lower side of the pipe 9. A number of such nozzles are provided at closely spaced intervals. These jet members, as shown, may be drilled so as to provide a frusto-conical discharge passage 16a converging inwardly to a throat portion 16b and then expanding to open into the discharge pipe 9. The jet member 16 may be of any convenient form,

to provide steam jets of any desirable character. Fan shaped jets may be desirable.

The operation of the apparatus is substantially self-evident. When distilling liquids in the shell 5 still illustrated, the steam spray sweeper is actuated in the manner provided in order to maintain a constant discharge of steam against the shell bottom and dislodge any deposits which may tend to form or settle out of the liquid contents. The steam discharge not only sweeps the bottom from side to side in oscillatory fashion, but also aids in the distillation step by its stripping action. The discharge of steam and the 10 oscillatory movement of the sweeper frame 15 through the body of the oil provides for positive agitation of the liquid contents.

Although the invention has been disclosed with reference to the more specific embodiments thereof, it should be apparent that numerous 20 modifications and structural changes may be made without departing from the inventive concept. It is not intended that the invention be limited by the specific details set forth for the purpose of illustration, but only by the appended 25 claims.

I claim:

1. In a shell still for liquids, means for preventing the deposition of solid matter on a heated surface of the shell, comprising a frame of inter- 30 communicating pipe members, means for uni- laterally supporting said frame longitudinally of

said shell, means for supplying steam to said pipe members, means for discharging steam from said frame in jets against the heated surface of said shell, and means for limited oscillation of the frame about its lateral axis. 5

2. In a shell still, a steam sweeper structure comprising a distributing pipe disposed longitudinally of the shell and mounted for axial rotation therein, a discharge pipe parallel to said distributing pipe and suspended therefrom in spaced 10 relation to the shell bottom, tubular connections between said pipes in communication with each, a plurality of discharge elements on said discharge pipe, directed toward the shell bottom, means for supplying steam to said distributing 15 pipe and means for limited oscillation of the structure. 15

3. In a heated liquid container, means for preventing deposition of solid matter on the heated inner surface thereof, comprising a pipe disposed 20 longitudinally of said container in closely spaced relation to said heated surface, a plurality of fluid discharge members opening from said pipe toward the heated surface, means for supplying a fluid to said pipe under pressure, and means 25 for oscillating the pipe laterally about the longitudinal axis of said container. 25

4. An apparatus according to claim 3 in which the pipe is disposed for oscillatory motion 30 through an arc of less than 180°. 30

EDWARD A. RUDIGIER.
